UNITED STATES PATENT OFFICE

110,400

DESIGN FOR A COMBINED DISPLAY AND ORDER CARD

Gilbert J. Rhodes, New York, N. Y.

Application May 5, 1938, Serial No. 76,985

Term of patent 3½ years

To all whom it may concern:

Be it known that I, Gilbert J. Rhodes, a citizen of the United States of America, residing in city of New York, county of New York, and State of New York, have invented a new, original, and ornamental Design for a Combined Display and Order Card, of which the following is a specification, reference being had to the accompanying drawings, forming part thereof,

Fig. 1 is a front view of a combined display and order card showing my new design in closed position.

Fig. 2 is a rear view thereof.

Fig. 3 is a front view of the combined display and order card in open position.

Fig. 4 is a front view of the combined display and order card showing the order card portion in closed position.

I claim:

The ornamental design for a combined display and order card, substantially as shown.

GILBERT J. RHODES.
